(57) **CLAIM**

The ornamental design for an equipment for distribution of electric power, as shown and described.

DESCRIPTION

FIG. 1 is a front, right side perspective view of an equipment for distribution of electric power with one modular cabinet unit in accordance with the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a rear, left side perspective view thereof;

FIG. 8 is a front, right side perspective view of a variant of the equipment for distribution of electric power of FIG. 1 with two modular cabinet units.

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a rear, left side perspective view thereof;

FIG. 15 is a front, right side perspective view of a variant of the equipment for distribution of electric power of FIG. 1 with three modular cabinet units.

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top plan view thereof;

FIG. 21 is a rear, left side perspective view thereof;

FIG. 22 is a front, right side perspective view of a variant of the equipment for distribution of electric power of FIG. 1 with four modular cabinet units.

FIG. 23 is a front elevational view thereof;

FIG. 24 is a rear elevational view thereof;

FIG. 25 is a left side elevational view thereof;

FIG. 26 is a right side elevational view thereof;

FIG. 27 is a top plan view thereof; and,

FIG. 28 is a rear, left side perspective view thereof.

The broken line portion of the figure drawings is included to show portions of the article that form no part of the claimed design.

1 Claim, 28 Drawing Sheets
